APPARATUS FOR CLOSING DUMP
CAR DOORS

Charles E. Zimmerman, Globe, Ariz., assignor to
Inspiration Consolidated Copper Company, a
corporation of Maine

Application February 11, 1950, Serial No. 143,615

7 Claims. (Cl. 105—292)

1

This invention relates to apparatus for closing the discharge doors of bottom-dump ore cars. More particularly the invention is concerned with a fluid-operated apparatus designed to replace the manually operated mechanism ordinarily provided for closing the doors of such dump cars.

Heretofore, after the doors of a bottom opening dump car have been opened to discharge ore carried by the car, it has been necessary, in order to close the doors, to manually operate a crank mechanism which raises the doors to closed position. The doors must then be maintained by the crank mechanism in the closed position until a latching mechanism, secured to the dump car, may be operated to lock the doors in such closed position. Because of the weight of the doors for an ordinary dump car, the manual closing requires considerable labor, is slow and tedious, and is not altogether safe. Additionally, in order to speed up the use of the manually operable closing mechanism, two men must be employed, one to operate the closing mechanism and another to operate the latching mechanism for locking the doors in closed position after the closing mechanism has been operated.

It is the object of this invention to provide a fluid-operated mechanism to take the place of the former manually operated mechanism and to accomplish the closing of the doors of a dump car quickly, safely and without the tedious and laborious manual effort that has heretofore been required. The invention contemplates the accomplishment of this object by a fluid-operated mechanism controlled entirely by a single valve means. The fluid-operated mechanism contemplated provides an equal closing force for each door of the dump car, whereby each door may be fully closed despite any resistance to closing encountered by another door. Furthermore, the fluid-operated mechanism for closing the doors includes a time-delay device, whereby the doors are automatically held in closed position for a predetermined period of time before the fluid-operated mechanism ceases to exert the closing forces on them so that the door latching means carried by the car may be operated to lock the doors in closed position safely and without any danger to the operator.

Briefly, the fluid-operated mechanism for closing the doors of a bottom-dump ore car comprises a pressure-tight cylinder mounted on the center sills of the car and provided with fluid under pressure through an opening in its lower end. A reciprocable piston, supporting an upwardly extending piston rod, is mounted in the cylinder and adapted to be moved upwardly under the pressure of fluid supplied to the cylinder. A sheave or pulley is attached to the upper end of the piston rod and freely supports a cable, the

2

opposite ends of which are connected to the car doors. Upon the admission of fluid under pressure to the cylinder the piston, piston rod, and pulley are moved upwardly, thereby drawing the cable upwardly, and as the cable is freely supported by the pulley, equal forces are provided to the car doors to urge them closed. The flow of fluid to and from the pressure-tight cylinder is controlled by a valve operable in one direction to permit the flow of fluid to the cylinder and in the opposite direction to permit the flow of fluid from the cylinder. The valve is so designed that it is normally urged in the latter direction. However, a latching mechanism is additionally provided whereby its operating handle may be maintained in the position in which the valve is operable to supply fluid to the cylinder. A time-delay device is associated with the operating handle of the valve to unlatch it after a predetermined interval and permit the valve to return to a position in which fluid already supplied to the pressure-tight cylinder may flow through it from, or out of, the cylinder. The time-delay device is operable in response to the position of the piston in the cylinder and/or in response to the volume and pressure of the fluid supplied to the pressure-tight cylinder, and is actuated when the piston has been moved upwardly in the cylinder to the position at which it lies when the car doors are closed. The period between this time and that at which the time-delay device has effectively acted to unlatch the valve-operating handle thereby releasing the fluid from the elevating cylinder is sufficiently long to permit the operation of the latching means by which the doors of the car may be permanently maintained in closed position.

For a more detailed description of one type of apparatus which falls within the scope of this invention, reference may be made to the accompanying drawings in which:

Fig. 1 is a perspective view of a bottom-dump ore car provided with a fluid-operated door closing mechanism according to my invention,

Fig. 2 is an end view of the car shown in Fig. 1 in which parts of the car are shown in section in order that my novel closing device may be seen more clearly,

Fig. 3 is a sectional view taken along line 3—3 of Fig. 2 and shows the cable raising mechanism and time-delay device,

Fig. 4 is a sectional view taken along line 4—4 of Fig. 2 and shows, in detail, the valve mechanism employed for controlling the flow of fluid to and from the door closing mechanism, and

Fig. 5 is a sectional view taken along line 5—5 of Fig. 2 showing more clearly the structure of the upper end of the cable-carrying piston rod and the guides therefor.

By reference to Figs. 1 and 2, a bottom opening dump car, and features thereof that are old, will first be described. The dump car has upright side walls 2 and sloping end walls 3, only one of each of which may be seen in the drawings. The bottom of the car is partially formed by downwardly opening doors 4 and 4' (Fig. 2) partially supported by shafts 5 and 6, which extend throughout the length of the car. The remainder of the bottom is formed by a longitudinally extending fixed member (or members) 7, which is triangular in cross-section so as to direct the car contents through the doors when the latter are opened by being pivoted downwardly about shafts 5 and 6. The car is adapted to be supported on railway rails 8 and 9 by a four-wheel truck 10 at each of its ends, only one truck being shown in the drawings. Each of the doors 4 and 4' is supported by a plurality of hinges 11 secured to the underside of the doors at spaced intervals along their longitudinal extent. The inner end of each hinge is formed with a loop 12, which is adapted to surround the longitudinally extending shaft 5 or 6 and to thereby support the inner end of the hinge and inner edge of the door. Each hinge 11 is of sufficient length to extend a short distance beyond an outer side wall 2 of the car when it supports a door in closed position. Door latches 13, one for each door hinge, are pivotally supported by pins 14 on the outer face of side sills 15 of the car. Connecting rods 16, one for each side of the car, connect the upper ends of the latches and are themselves connected by a transversely extending rod 17 by which all the latches on the car may be pivoted or operated from one position. The lower ends of the latches have projecting portions 18 which are adapted to pass beneath the outer ends of the door hinges when the doors are in closed position and to thereby support the hinges and therefore the doors. The outer end of each door hinge 11 is formed with a rearwardly and upwardly extending portion 19 which effectively prevents the lower end of its corresponding latch from sliding off the end of the hinge when the latch and the hinge are in locking relationship. Pivot brackets 20, extending partially beneath doors 4 and 4' and secured thereto at spaced intervals along the length of the doors, are supported by shafts 5 and 6 to which they are fixedly secured as by keys. Operating brackets 21 are also secured to shafts 5 and 6 by keys at the end of the car outside sloping wall 3 thereof and normally extend upwardly above the plane of the bottom of the car.

The structure above described is old in the art and for its operation there was formerly supported at the end of the car between operating brackets 21, a crank and windlass assembly by which the operating brackets 21 could be pivoted upwardly to close car doors 4 and 4'. With that closing mechanism, however, which was manually operated, the closing of the doors was a tedious and laborious operation requiring considerable time. Additionally, the mechanism had to be manually maintained in door-closing condition until the latches 13 could be operated to lock the doors in closed position. Also, as the mechanism was individually secured to brackets 21, the force supplied by the crank and windlass mechanism to close the doors was not equalized between the doors and if, for any reason, one of the car doors would not close, the other would not close either.

The apparatus of my invention is aimed at the replacement of the former manually operated mechanism by an automatically operated mechanism which provides equal closing forces to the car doors and which also provides a time lag after it has been operated to close the doors and before it has been deactivated and returned to its original position, in which the latches 13 may be safely pivoted to secure the doors in closed position. To this end my apparatus comprises a fluid pressure cylinder 22 supported at one end of the car on the center sill structure 23 of the car between longitudinally extending shafts 5 and 6. For the purposes of this description and as contemplated for actual use, the fluid to be used in the operation of the mechanism will be compressed air. An inlet conduit 24 is provided to supply compressed air to the lower end of cylinder 22. A piston 25 (Figs. 3 and 5) is reciprocably mounted in cylinder 22 and supports on its upper side a piston rod 26 of tubular shape which extends through an opening 27 in the upper wall 28 of cylinder 22. A pulley or sheave 29 is supported on a bearing 30 secured in the upper end of tubular piston rod 26. Guide followers 31 are secured to the outer side of piston rod 26 and are adapted to ride between guides 32 of a guiding framework which is supported on the upper end 28 of cylinder 22. For further support the upper ends of each of the members or elements 32 of the guiding framework are additionally secured to end wall 3 of the dump car. As seen most clearly in Fig. 2, each pair of guiding elements 32 is provided with a pair of sheave-supporting members 33 having a series of corresponding holes 34 in which bearings for guiding sheaves or pulleys 35 may be mounted. A cable 36 (Fig. 2) is adjustably attached at its opposite ends to operating brackets 21 of the car doors by means of auxiliary brackets 37 secured to operating brackets 21 and each having a series of holes therein whereby the position of attachment may be varied. Pulley or sheave 29 supported at the upper end of piston rod 26 is adapted to freely engage the center portion of the cable which passes over it and which passes beneath fixed guiding sheaves 35. It will thus be seen that when compressed air is supplied to the lower end of cylinder 22 through conduit 24 that piston 25 and piston rod 26 will be urged upwardly and that pulley or sheave 29 will in turn draw the ends of cable 36 inwardly and upwardly to pivot operating brackets 21 on shafts 5 and 6, thereby raising the car doors from their positions as shown in dotted lines in Fig. 2 to their closed positions as shown therein in solid lines. Because of the fact that the cable is not fixedly secured to the piston rod 26 or to any part of the compressed air elevating mechanism the forces applied by it to each of the doors is always equal in degree. An opening is formed in end wall 3 of the car to permit the piston rod 26 to be elevated a sufficient distance to close tightly the doors and a box-like covering member 3' is provided to cover the opening to prevent ore loaded in the car from passing through the opening.

The supply of compressed air to conduit 24 is controlled by a three-way valve shown in detail in Fig. 4. Briefly, it comprises a block 38 having a valve chamber 39 in communication with which is conduit 24 which leads from the valve to cylinder 22 and conduit 40 leading from a compressed air supply conduit 40' (Fig. 2) to the

valve. A standard valve element 41 is reciprocably mounted within valve chamber 39 and is provided at each end with an air-tight piston cup 42. When in the position shown in Fig. 4, the valve element places conduit 24, and therefore the interior of cylinder 22, in communication with the atmosphere through the valve and a vent 43. A valve operating handle or lever 44, loosely pivoted by a pin 45 to a portion 46 of the valve body 38, is provided to urge valve element 41 inwardly in valve chamber 39. A roller bearing 47 is supported in the outer end of valve element 41 to receive, with negligible friction, the force supplied by lever 44 to the valve element. When the valve element 41 is urged to its inner position, as will be the case when lever 44 is moved to its position shown in dotted lines in Fig. 4, conduit 24 is placed in communication with conduit 40 which leads from the source of compressed air, and therefore compressed air is supplied to cylinder 22. The valve, as described, is not in itself a part of my invention.

A bracket 48 is supported by the same portion of the framework that supports the valve and is provided with steps 49 and 50. Operating lever 44 rests on step 50 when the valve is in venting position and on step 49 when the valve is in air supplying position. When the valve element 41 is moved inwardly within chamber 39, a certain amount of air contained in the inner end of chamber 39 is compressed between that end of the chamber and the inner end of the valve element because of the fact that piston cup 42 at this end of the valve element is air tight. In other words, when valve element 41 is moved inwardly in the valve chamber, it is so moved against the pressure of the compressed and trapped air. Therefore, it will be clear that the valve element 41 is always urged outwardly either by compressed air from conduit 40 or by the compressed air entrapped at the inner end of chamber 39. When lever 44 is moved to the dotted line position, it is so moved against an opposing force exerted on the valve element and when it is in dotted line position on step 49 and is released it will be urged against the shoulder between steps 49 and 50 and remain there until positively lifted above the shoulder so that it may return to its original position, and thus piston 25 and its supported structure will remain in their uppermost, or door closing, positions until the lever 44 is released.

Referring again to Fig. 3, I will now describe the novel time-delay device by which the operating lever 44 is released from step 49 a certain predetermined length of time after the compressed air operating mechanism effectively closes the doors of the car. A pressure-tight cylinder 51, in which there is contained a fixed quantity of fluid 52, such as oil, has its upper end connected by a conduit 53 to the interior of cylinder 22 at a point just below the position in which piston 25 will be when it has moved upwardly in cylinder 22 to effectively close the doors of the car. A second fluid or pressure-tight cylinder 54 is supported on bracket 48 by a U-clamp 55 directly beneath step 49 of the bracket and has its lower end connected by a conduit 56 to the lower end of cylinder 51. Conduit 56 is connected to cylinder 54 by a connecting member 57 having therein a restricted orifice 58. A piston 59 is reciprocably mounted in cylinder 54 and is spring urged towards the bottom of the cylinder by a spring 60 contained in the cylinder. A piston rod 61 is supported by piston 59 and ex-

tends through the upper end of cylinder 54, its own uppermost end being positioned just below the lever 44 on step 49 of bracket 48 when piston 59 rests at the lower end of cylinder 54. Piston 59 is adapted to be urged upwardly against the force of spring 60 when compressed air is admitted to cylinder 51 through conduit 53, thereby forcing oil 52 through conduit 56 and restricted orifice 58 into cylinder 54. Compressed air is, of course, admitted to conduit 53 only when the operating lever 44 of the three-way valve is resting on step 49 and compressed air has thus been supplied to cylinder 22. When piston 59 rises in cylinder 54, piston rod 61 abuts the lower side of the operating lever and raises it, thereby releasing it from engagement with the shoulder between steps 49 and 50 and permitting it to return to its position, as shown in solid lines in Fig. 4. Because of the restricted orifice 58, through which oil must pass from cylinder 51 to cylinder 54, the flow of oil between these cylinders is relatively slow and a certain period elapses between the time when compressed air is initially admitted to cylinder 51, above the oil level therein, and the time when a sufficient amount of oil has been admitted to cylinder 54 to raise the piston and the piston rod to release operating lever 44. It is contemplated that during this period, which may be made as long as desired as, for instance, by varying the size of the orifice 58 or the size of spring 60, the door latches 13 of the car may be operated to lock the doors in closed position.

A shield 62 (Fig. 1) is secured to the upper edge of end wall 3 of the car and extends outwardly therefrom over my apparatus to protect it from ore which may overflow the end of the car or which may be dropped over the end during loading.

The operation of my fluid-operated door closing mechanism in its entirety is briefly as follows: Assuming that the doors of the car are in opened position and that therefore piston 25 is at its lowest position in cylinder 22, the three-way valve is operated by lever 44 to admit compressed air to cylinder 22, as described, operating lever 44 being maintained on step 49 by the shoulder between steps 49 and 50. Under the influence of the compressed air so admitted to cylinder 22, piston 25 moves upwardly in the cylinder, thereby moving sheave or pulley 29 upwardly and drawing cable 36 inwardly and upwardly to pivot the doors 4 and 4' of the car to closed position under equal forces. When the doors have thus been pivoted to closed position and piston 25 is in its uppermost position, the interior of cylinder 22 is in communication with the interior of cylinder 51 through conduit 53 and compressed air is thereby supplied to cylinder 51 above the level of the oil therein. Oil 52 then begins to flow through conduit 56 and restricted orifice 58 into cylinder 54 to force piston 59 and piston rod 61 upwardly therein. After a predetermined length of time, sufficient oil will have been admitted to cylinder 54 to cause piston rod 61 to rise sufficiently to release operating lever 44 of the valve from step 49, thereby permitting valve element 41 to return to its normal position. As stated, during this period of time, latches 13 may be placed in locking position below the outer ends of door hinges 11 to thereby lock the doors of the car closed. When valve element 41 returns to its original position, cylinder 22 is vented through conduit 24, the valve, and vent 43, and piston 25 descends within cylinder 22 to its original position where it remains

until it has to be used again to close the car doors. Compressed air for the operation of the mechanism may be provided from any source, but it is contemplated that it will be supplied from the compressor of the locomotive engine used to draw the dump car by means independent of the brake line or system.

I claim:

1. In a dump car having a pair of downwardly opening doors and latching means for maintaining the doors in closed position after they have been closed, apparatus for closing the doors which comprises a cable secured at one end to one of the doors and at its other end to the other door, means freely-engaging the cable intermediate the cable ends, and means for forcing said cable engaging means upwardly to close the doors, whereby the closing force acting upon one door is always equal to the closing force acting upon the other door.

2. In a dump car having a pair of downwardly opening doors and latching means for maintaining the doors in closed position after they have been closed, apparatus for closing the doors which comprises a fluid pressure cylinder, a piston within said cylinder and movable therein under the force of a fluid admitted to the cylinder under pressure, a piston rod secured to said piston, means for supplying fluid under pressure to the cylinder below the piston, a cable secured at one end to one of the doors and at its other end to the other door, and means supported on the piston rod and freely engaging the cable intermediate the ends of the cable, whereby when fluid under pressure is supplied to the cylinder the piston therein is urged upwardly thereby urging the cable engaging means upwardly and exerting equal forces upon the doors to urge them to closed position.

3. In a dump car having a pair of pivotally mounted doors which open downwardly, a bracket secured to the pivot support of each door for pivotally closing the door, and latching means for maintaining the doors in closed position after they have been closed, apparatus for closing the doors which comprises a fluid pressure cylinder mounted between the pivot supports, a piston within said cylinder and movable therein under the force of fluid admitted to the cylinder under pressure, a piston rod secured to said piston, means for supplying fluid under pressure to the cylinder below the piston, a cable secured at one end to one of the brackets and at its other end to the other bracket, and means supported on the piston rod and freely engaging the cable intermediate the ends of the cable, whereby when fluid under pressure is supplied to the cylinder the piston therein is urged upwardly thereby urging the cable engaging means upwardly and exerting equal forces upon the brackets secured to the pivot supports to urge the doors closed with equal force.

4. In a dump car having downwardly opening doors, means operated by fluid under pressure for closing said doors and latching means for maintaining the doors in closed position after they have been closed, apparatus for controlling the fluid-operated means which comprises valve means for controlling the flow of fluid to and from said fluid-operated means, means for moving the valve to a position to supply fluid under pressure to the fluid-operated means, means for maintaining said valve in said position, a time-delay device responsive to movement of the fluid-operated means to door closing position for mov-

ing said valve means to its original position in which the supply of fluid to the fluid-operated means is discontinued and in which fluid that has been supplied to the fluid-operated means is permitted to flow from the fluid-operated means, said time-delay device providing a period of time in which the car doors are held closed by the fluid-operated means and during which the latching means may be adjusted to maintain the doors in closed position.

5. In a dump car having downwardly opening doors, means operated by fluid under pressure for closing said doors and latching means for maintaining the doors in closed position after they have been closed, apparatus for controlling the fluid-operated means which comprises valve means for controlling the flow of fluid to and from said fluid-operated means, manually operable means for moving the valve to a position to supply fluid under pressure to the fluid-operated means, means for maintaining said valve in said position, said valve when in said position being acted upon by a force which urges it toward its original position, and a time-delay device responsive to the volume and pressure of the fluid supplied to the fluid-operated means for releasing the valve so that it returns to its original position in which the supply of fluid to the fluid-operated means is discontinued and in which fluid that has been supplied to the fluid-operated means is permitted to flow from the fluid-operated means, said time-delay device providing a period of time in which the doors are held closed by the fluid-operated means and during which the latching means may be adjusted to maintain the doors in closed position.

6. Apparatus in accordance with claim 5 in which the time-delay device comprises a pressure-tight cylinder containing a supply of fluid, a second cylinder, a piston reciprocably mounted in said second cylinder, a piston rod supported by said piston and extending through one end of said second cylinder and adapted to act upon said valve means to release the valve so that it may return to its original position, a conduit connecting one end of said first-mentioned pressure-tight cylinder to the fluid-operated means, a conduit having a restricted orifice and connecting the other end of said first-mentioned cylinder to the end of said second cylinder below the piston contained therein, whereby the piston and its supported piston rod are urged away from said last-mentioned end of the second cylinder when the fluid under pressure in the fluid-operated means is permitted to enter the first-mentioned connecting conduit.

7. Apparatus in accordance with claim 6 which includes spring means contained in the second cylinder and acting upon the piston therein to oppose movement of the piston as a result of the admission into said second cylinder of fluid from the first-mentioned cylinder.
